UNITED STATES PATENT OFFICE.

HERBERT R. KEITHLEY, OF BUFFALO, NEW YORK.

RAILWAY-CAR-TRUCK BOLSTER.

SPECIFICATION forming part of Letters Patent No. 727,149, dated May 5, 1903.

Application filed October 15, 1902. Serial No. 127,371. (No model.)

To all whom it may concern:

Be it known that I, HERBERT R. KEITHLEY, a citizen of the United States, residing at Buffalo, in the county of Erie and State of New York, have invented new and useful Improvements in Railway - Car - Truck Bolsters, of which the following is a specification.

This invention relates more particularly to a metallic box-bolster for railway-car trucks.

10 Built-up box-bolsters have been produced heretofore, but they have either been formed in part or in whole of pressed-steel parts, requiring the employment of specially-designed and expensive dies or forming-machines, or 15 they have been built up in part or in whole of rolled shapes, which in order to secure the necessary strength and stiffness have been needlessly multiplied and of complicated arrangement, thus increasing the weight and 20 cost of the bolster.

The object of this invention is to provide an exceedingly light, strong, and cheap box-bolster which is built up of the minimum number of pieces and composed entirely of commercial rolled shapes and plates having only 25 simple straight bends and which can be readily formed in metal-working shops as ordinarily appointed.

While the bolster herein described and 30 shown in the drawings is primarily intended for a truck-bolster, it is not necessarily restricted to such use.

In the accompanying drawings, Figure 1 is a side elevation of a bolster embodying the 35 invention. Fig. 2 is a longitudinal section thereof. Fig. 3 is an end view thereof, and Fig. 4 is a central transverse section thereof.

Like letters of reference refer to like parts in the several figures.

40 The bolster is composed of two separated substantially vertical side plates A, a top plate B, connecting the upper edges of the side plates, and a bottom channel beam or bar C. The side plates are provided at their upper edges with straight horizontal flanges D, which are formed by the integral inwardly-bent upper edges of the plates. These flanges extend beneath and support the top plate, which is rigidly attached to the flanges by 45 vertical rivets d. The top plate bears on the

flanges, which thus relieve the rivets d from any shear due to the load carried by the bolster. The side plates are deeper at their middle portion than at their ends, or the lower edges of the middle portions extend down below the lower edges of the end portions. The channel forming the bottom of the bolster is arranged with its flanges projecting upwardly, and the lower portions of the side plates are arranged inside of the channel-flanges, to which they are securely attached throughout the length of the bolster by rivets e. The side plates are provided at the lower edges of their end portions with integral horizontal straight flanges F, which project inwardly and bear on the upper face of the channel-web, to which they are attached by rivets f. The ends of the bolster sides thus have a direct broad flat bearing on the bottom channel and relieve the rivets connecting the sides 70 and bottom channel from any vertical shear due to the load supported by the bolster and which is necessarily concentrated at the ends of the bolster, which rest on the supporting-springs. While the side plates are provided with top and bottom flanges, these flanges are 75 straight and are formed by simple straight bends, which can be made by the usual flanging-machines. There are no bends requiring special dies or forming-machines. 80

The bolster is composed of only four simple parts riveted together, and while it can thus be readily and cheaply made it is very strong, rigid, and durable.

I claim as my invention—

1. A bolster comprising a bottom channel arranged with its flanges projecting upwardly, side plates arranged inside of and riveted to said channel-flanges, said side plates having integral bottom flanges at their ends which bear on the upper face of the channel-web, and integral inwardly-extending top flanges, and a top plate which is supported by and riveted to said top flanges, substantially as set forth. 85

2. A box-bolster which is deeper at its middle portion than at its end portions, and comprising a bottom channel arranged with its flanges projecting upwardly, substantially vertical side plates arranged inside of and riv- 100

eted to said channel-flanges, said side plates having integral straight bottom flanges at their ends which bear on the upperface of the channel-web, and integral straight top flanges which project toward each other, and a top plate which bears on and is riveted to said top flanges, substantially as set forth.

Witness my hand this 11th day of October, 1902.

HERBERT R. KEITHLEY.
